UNITED STATES PATENT OFFICE.

PARKER J. O'BRIEN, OF BROOKLYN, NEW YORK.

CAP.

Application filed November 19, 1921, Serial No. 516,252. Renewed August 16, 1924.

To all whom it may concern:

Be it known that I, PARKER J. O'BRIEN, a citizen of the United States, and residing at Brooklyn, in the county of Kings and State of New York, have invented certain new and useful Improvements in Caps, of which the following is a specification, such as will enable those skilled in the art to which it appertains to make and use the same.

This invention relates to caps and particularly to caps of the knitted class, and the object of my invention is to provide a cap of the class specified with a muffler portion which is normally supported upon the body portion of the cap and is adapted to be moved into operative position and passed around the neck of the wearer; a further object being to provide a cap of the class specified with ear-lap portions normally supported in connection with the body portion of the cap and which are adapted to be passed downwardly over the ears and beneath the chin of the wearer, and the end portions of the separate flaps secured beneath the chin, and the muffler portion of the cap being also adapted to be secured to the attaching means of said ear-lap portions, and with these and other objects in view the invention consists in a cap of the class and for the purpose specified which is simple in construction, neat and ornamental in appearance in the several uses thereof and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a side view of the cap indicating the same upon the head of the wearer with the several parts thereof in their normal position;

Fig. 2 a view similar to Fig. 1 showing the ear-laps in their operative position;

Fig. 3 a front view slightly in perspective showing the ear-laps as well as the muffler portion of the cap in operative positions;

Fig. 4 an inside view of the cap detached

and showing the ear-lap and muffler portions thereof extended;

Fig. 5 a view similar to Fig. 1, but showing a modified form of construction; and,

Fig. 6 a view similar to Fig. 4 but showing a detail view of the cap illustrated in Fig. 5.

In Figs. 1 to 4 inclusive, I have shown one form of my improved cap which comprises a main cap body portion 10 of the desired shape and construction, said cap being provided at the front end portion thereof with a turned up part 11 which gives a neat finish and ornamental appearance to the front portion of the cap and to the back portion of the cap is secured a muffler member 12 of the approximate shape shown in detail in Fig. 4 of the drawing, and the outer corner portions of which are rounded as shown at 13 to form approximately pointed ends 14 provided with button-holes 15 or other means of attaching said end portions of the member 12 to a suitable attaching device, or to each other as the case may be when in operative position, and when in inoperative position said end portions are adapted to be connected with buttons 16 or other attaching devices and secured to the body portion 10 of the cap at the opposite sides thereof, as clearly illustrated in Fig. 2 of the drawing.

The side portions of the cap are provided with ear-laps 17, the free end portions of which are approximately V-shaped in form as shown at 18 and provided with button-holes and the like 19 whereby said ear-laps

may be connected with buttons or other attaching devices 20 secured to the side portions of the body 10 of the cap near the top thereof when said ear-laps are in their inoperative position as shown in Fig. 1 of the drawing, and one of said ear-laps 17 is pro-

vided on the inner face thereof when the ear-laps are in the position shown in Fig. 1 with the button 21, whereby the other ear-lap 17 may be connected with the first

named ear-lap below the chin of the wearer when said ear-laps are in their operative position as shown in Figs. 2 and 3 of the drawing.

It will be also noted on a consideration of Fig. 3 of the drawing that the end portions

of the muffler member 12 are also attached to the button 21 when said member 12 is in its operative position, and the rounded corner portions 13 produce a V-shaped effect, as

- 5 shown at 22 in Fig. 3 of the drawing at the front neck portion of the wearer beneath the chin thus giving a neat and finished appearance at such point, and will permit of the exposure of a necktie or the like there-
10 through and will present a dressy effect.

With my improved construction as shown in Figs. 1 to 4 inclusive, it will be apparent that the ear-laps 17 may be used independent of the muffler, but in very cold or stormy
15 weather and when it is desired to protect the back of the head and neck portion of the wearer, the muffler member 12 may be folded downwardly and the ends thereof connected with the button 21, as shown in Fig.
20 3 of the drawing. In other words, I provide a cap of the class specified which has three independent uses, one as a cap proper as shown in Fig. 1, the second as a cap provided with ear-laps as shown in Fig. 2, and
25 the third as a cap in the form of a helmet in which the ear-laps and muffler member 12 produce a helmet effect of the entire device.

In Figs. 5 and 6, I have shown a slight
30 modification of the construction shown in Figs. 1 to 4 inclusive, in which the muffler member 12 is of greater length than the muffler member 12 in the construction shown in Figs. 1 to 4 inclusive, and in this form of
35 construction the end portions of the muffler member 12 are approximately V-shaped in form as shown at 23 and are provided with button-holes 24 adapted to be normally connected with buttons 25 secured to the
40 turned-up portion 11 of the cap, or the opposite sides thereof, as clearly shown in Fig. 6 of the drawing and, in this construction, it will be apparent that the buttons 16 employed in the construction shown in Figs.
45 1 to 4 inclusive, will be limited but otherwise the construction is precisely the same as that shown in Figs. 1 to 4 inclusive.

Another feature of the construction shown in Figs. 5 and 6 lies in the fact that
50 the turned-up portion 11 may be used as a peak by merely extending the central rounded portion 26 thereof outwardly when the cap is in use, and this may also be done with the construction shown in Figs. 1 to
55 4 inclusive, if desired, or the turned-up portion may be affixed to the body 10 of the cap.

It will be understood that the cap shown in Figs. 5 and 6 will be capable of the three separate uses as with the cap shown in Figs.
60 1 to 4 inclusive, and while I have stated that I preferably make the cap and the various parts thereof of knitted material, it will be apparent that I am not necessarily limited to the material employed, and various other
65 changes in and modifications of the construc-

tion herein shown and described may be made, within the scope of the appended claims, without departing from the spirit of my invention or sacrificing its advantages.

Having fully described my invention, 70 what I claim as new and desire to secure by Letters Patent, is:—

1. A cap of the class described comprising a body portion, a muffler member and ear-laps independent of said muffler member, 75 said muffler member and ear-laps being adapted to be normally supported in connection with the body portion of the cap and said ear-laps being adapted to be passed downwardly over the ears of the wearer, 80 means for connecting the free end portions of said ear-laps beneath the chin of the wearer, and said muffler member being adapted to be passed around the neck of the wearer and to be detachably connected with 85 the means for connecting the end portions of said ear-laps.

2. A cap of the class described comprising a body portion, a muffler member and ear-laps independent of said muffler member, 90 said muffler member and ear-laps being adapted to be normally supported in connection with the body portion of the cap and said ear-laps being adapted to be passed downwardly over the ears of the wearer, 95 means for connecting the free end portions of said ear-laps beneath the chin of the wearer, said muffler member being adapted to be passed around the neck of the wearer and to be detachably connected with the means for connecting the end portions of said ear-laps and the front of the body portion of the cap being provided with a turned-up portion. 100

3. A cap of the class described, comprising a head or body portion, a muffler member attached to the rear edge of the head or body portion, ear-laps independent of said muffler member and attached to the side edges of the head or body portion, said muffler member being normally folded upon the head or body portion, and the ends thereof directed forwardly, means for detachably securing said ends to the head or body portion, and said ear-laps being adapted to normally be folded upon said head or body portion, means for detachably securing said ear-laps thereto, said ear-laps and the ends of said muffler member being overlapped on said head or body portion, and said ear-laps being adapted to be passed downwardly over the ear of the wearer and the ends thereof connected beneath the chin of the wearer, said muffler member being adapted to be extended around the neck of the wearer and detachably secured to the attaching means of said ear-laps. 115

4. A cap of the class described, comprising a head or body portion, a muffler mem- 120
125
130

ber attached to the rear edge of the head or body portion, ear-laps independent of said muffler member and attached to the side edges of the head or body portion, said muffler member being normally folded upon the head or body portion, and the ends thereof directed forwardly, means for detachably securing said ends to the head or body portion, and said ear-laps being adapted to normally be 10 folded upon said head or body portion, means for detachably securing said ear-laps thereto, said ear-laps and the ends of said muffler member being overlapped on said head or body portion, and said ear-laps be- ing adapted to be passed downwardly over 15 the ears of the wearer and the ends thereof connected beneath the chin of the wearer, said muffler member being adapted to be extended around the neck of the wearer and detachably secured to the attaching means 20 of said ear-laps, and the front edge of said head or body portion being provided with an upturned portion.

In testimony that I claim the foregoing as my invention I have signed my name this 25 16th day of November, 1921.

PARKER J. O'BRIEN.
